UNITED STATES PATENT OFFICE.

JOHN W. SMITH, OF JERSEY CITY HEIGHTS, NEW JERSEY.

ICE-BUNKER.

SPECIFICATION forming part of Letters Patent No. 223,550, dated January 13, 1880.

Application filed September 19, 1879.

To all whom it may concern:

Be it known that I, JOHN W. SMITH, of Jersey City Heights, in the county of Hudson and State of New Jersey, have invented a new and 5 Improved Ice-Bunker, of which the following is a specification.

Figure 1 is a rear-side elevation of the ice-bunker. Fig. 2 is an end elevation of the bunker. Fig. 3 is a front elevation, part being broken away. Fig. 4 is a cross-sectional elevation taken through the line x x , Fig. 3.

Similar letters of reference indicate corresponding parts.

The object of this invention is to furnish a 15 bunker for holding ice in markets, hotel provision-rooms, vessels, and other places where a room is to be kept cool, so constructed as to effect a great saving of ice, while keeping the room cooler than the ordinary bunkers.

20 The invention consists of an ice-bunker having frame, casings, inclined bottom, doors, and inlets, as well as outlets, for air, as hereinafter described.

A represents the frame of the bunker, which 25 is supported upon legs or a suitable frame-work.

The bunker is incased with sheet metal B, wood, or other suitable material, attached to the inner surface of the frame-work A.

30 The bottom C of the bunker is inclined, as shown in Figs. 1 and 3, and has a flat surface, so that the ice may lie smoothly upon it, and may thus be prevented from melting so rapidly.

The rear side of the bunker is designed to 35 be placed against the side of the room, and has openings D formed through the upper part of its casing for the admission of air to be cooled. By this arrangement the upright timbers of the frame A form passages, through 40 which the air must pass and be partially cooled by contact with the casing B before entering the bunker.

In case the bunker cannot stand against 45 a wall, a casing should be attached to the outer surface of the rear-side timbers to form the air-passages.

In the middle and lower part of the front-side casing, B, are formed openings E for the egress of the cold air.

To the outer surface of the front-side timbers of the bunker-frame are attached casings F to form air-passages, which passages are closed at their upper ends, and are provided with doors G at their lower ends, so that they may be opened and closed as may be required. 50

In the rear end of the bunker is a door, H, through which the ice is put in, and in the lower part of the front end is formed a small door, I, for the egress of cold air. Usually a sufficiently low temperature can be obtained 55 by opening the door I; but when a lower temperature is required, one or more of the doors G may be opened.

The side edges of the bottom C project beyond the side casing, B, and are slightly bent 60 upward, as shown in Fig. 4, to form shallow channels J, through which drip-water may flow down to the drip apron or spout K at the lower end of the inclined bottom, and pass thence to the waste-water receiver. With this 65 construction any currents of air set in motion by opening and closing the door of the room and any inrush of warm air through the open door cannot impinge directly upon the ice, as they can only reach the ice by passing up 70 through the side passages of the bunker, and will thus be checked, so that very little ice 75 will be melted in this way.

Having thus described my invention, what 80 I claim as new, and desire to secure by Letters Patent, is—

The ice-bunker consisting of the frame A, having attached casings F, and the case B, having openings D E, inclined bottom J, and doors G H, substantially as described.

JOHN W. SMITH.
